CLAIM

The ornamental design for a car, toy car replica, and/or other replicas, as shown and described.

DESCRIPTION

FIG. 1 is a front and right side perspective view of a car, toy car replica and/or other replicas showing my new design;
FIG. 2 is a front elevation view thereof;
FIG. 3 is a right side elevation view thereof;
FIG. 4 is a rear elevation view thereof;
FIG. 5 is a left side elevation view thereof;
FIG. 6 is a top plan view thereof; and,
FIG. 7 is a bottom plan view thereof.
